UNITED STATES PATENT OFFICE.

RODNEY G. RICHARDSON, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed June 29, 1917. Serial No. 177,653.

To all whom it may concern:

Be it known that I, RODNEY G. RICHARDSON, a citizen of the United States of America, and a resident of Chicago, county of 5 Cook, and State of Illinois, have invented certain new and useful Improvements in Automatic Telephone Systems, of which the following is a specification.

My invention relates in general to automatic telephone systems, in which connections are established automatically through the medium of automatic switches at the exchange, and involves a number of features, among which may be mentioned the provision 10 of new and improved circuits for individual line or trunk selecting switches; the provision of new and improved circuits for selector switches; the provision of new and improved connector switches of large capacity and well adapted for straight line or party line service; and the provision of a new, improved, and much simplified system of selective ringing for automatic party lines which, although especially designed 15 for use in a system employing my improved connector switches, may also be used with connectors of other types.

The apparatus and circuits involved in carrying out the foregoing and other useful 20 objects will be fully described and explained hereinafter, reference being had to the accompanying drawings, in which Figs. 1 and 2 when taken in order with corresponding lines at the ends thereof in alignment, represent diagrammatically a complete circuit connection between a calling substation A and a called substation A' in a system embodying the principles of my 25 invention; while Fig. 3 shows the numbering of one of the bank levels of my improved connector switch.

Referring to Fig. 1 of the drawings, the substation A may be of any approved automatic type such, for example, as the one 30 disclosed in the British Patent to Martin, No. 1419 of 1910. As illustrated, it comprises essentially the receiver 2, transmitter 3, switchhook 4, ringer 5, and condenser 6. Being an automatic substation, there is also 35 provided a pair of impulse springs 7 and 8 which may be controlled by the impulse wheel 9 through the medium of a finger hole dial (not shown).

The line conductors 12 and 13 extend to 40 the exchange where they terminate in the

individual line switch C, in a manner to be described more fully in connection with the showing of the called line in Fig. 2. The line switch C may be briefly described as a rotary line switch whose movable terminals or wipers have no normal position and have movement in a forward direction only. A construction which permits of the continuous forward movement of the line switch wipers is illustrated in the U. S. Patent to 60 Dietl No. 1,126,727. I prefer, however, to use double instead of triple wipers, and a bank comprising 25 bank contact sets. I provide an improved circuit for a rotary line switch of this character, whereby ordinary manual relays may be used having no mechanical connections between their armatures.

Three hundred or more of these individual line switches may be given access to a 75 group of 25 trunk lines, each of which trunk lines terminates in a first selector switch. One of the trunk lines to which the individual line switch C has access, is the trunk line extending to the first selector E (Fig. 80 1), which may be of the general type of selector switch shown in the patent to Keith, Erickson, and Erickson, No. 815,321, granted March 13, 1906. The side switch and private magnet are omitted, however, and the circuits are modified in accordance with the two wire system of control. Further 85 modifications in accordance with my invention provide an exceedingly simple and efficient circuit for a selector switch of this 90 character, as will be fully explained hereinafter.

The selector E, together with a plurality of similar selectors, has access to a plurality of groups of trunk lines, the trunk lines of each group terminating in a group of connector switches. One of the trunk lines to which the selector E has access is shown in the drawings as extending to the connector H 100 (Fig. 2). The connector H may be of the general type of connector switch shown in the United States Letters Patent No. 815,176, granted March 13, 1906, to Keith, Erickson, and Erickson, except that the circuits are modified in accordance with modern two wire 105 practice, as in the case of selector E, and are further modified in order to accomplish the objects of my invention, as will be fully explained hereinafter. There are also some slight mechanical differences. Instead of the 110

usual three position side switch, the side switch on my improved connector has four positions, the escapement springs controlled by the private magnet being each provided with an extra notch. There is also provided, in addition to the usual vertical off-normal springs, a pair of rotary off-normal springs, indicated by reference characters 124 and 125, which are closed upon the second rotary step of the shaft. It should be mentioned also that the connector shaft is provided with sufficient teeth in the rotary ratchet portion thereof to enable it to take twenty rotary steps instead of the usual ten.

15 The bank of my improved connector switch is similar to the bank shown in the patent to Keith and the Ericksons above mentioned, that is, it is composed of contact sets arranged in ten horizontal rows or levels. Each level, however, instead of having ten contact sets, has twenty contact sets, thereby giving the connector a capacity of two hundred lines. Although physically the entire two hundred lines accessible to 25 a group of connectors may be considered as comprising a single group, nevertheless, since the usual decimal numbering and trunking scheme is used, they are for numbering purposes divided into two groups of 30 one hundred lines each. These I term the odd hundred and the even hundred, or the one hundred and the four hundred. Contact sets in the two hundreds are disposed alternately in the connector bank. Thus, 35 referring to Fig. 3, which shows the numbering of the first level, the first level contact sets of the one hundred, being contact sets numbered from 111 to 110, inclusive, are the first, third, fifth, seventh, etc., contact sets in the level, while the first level contact sets of the four hundred, comprising contact sets numbering from 411 to 410, inclusive, are the second, fourth, sixth, eighth, etc., contact sets. It will be understood from 40 the foregoing, that the third from the last digit in every telephone number is either 1 or 4. In considering the trunking, this digit may be neglected; and it may be stated that the trunking in the system shown 45 is precisely the same as in the usual and well known three digit percentage system, the extra digit being inserted simply to control the odd or even hundreds selection at the connectors. It will be understood, however, 50 that since each group of connectors has access to two hundred lines instead of to one hundred, there must be provided a larger number of connectors in each group. To take care of this the selector switches are 55 preferably provided with two hundred point banks like the connectors. Fifteen or sixteen contact sets or as many as are necessary to handle the traffic may be used in each level.

60 The bank wires from each group of connectors, commonly called normal conductors, are formed into cables and extend to and terminate on the horizontal side of an intermediate distributing frame (I. D. F.), where the odd and even hundreds of each 65 group are preferably separated, the normal conductors from each hundred being arranged in consecutive order. In general the preferred arrangement of the main and intermediate distributing frames and the cross 70 connecting scheme used is similar to the disclosure in the Australian Patent No. 15,525 of 1920. In the drawing the contact set comprising bank contacts 183, 184, and 185 is assumed to be an odd hundred contact set in 75 the first level, and its normal conductors terminate in the terminals 190, 191, and 192 on the horizontal side of the I. D. F. The contact set comprising bank contact sets 186, 187, and 188 is assumed to be an even hundred contact set in the second level, and its 80 normal conductors extend to terminals 193, 194, and 195 on the horizontal side of the I. D. F. The drawing being purely diagrammatic, does not show the relative position of the terminals but only the connections. As illustrated, the two sets of normal conductors serve as called line branches for the party line 212-213, which has two 85 substations A' and A''. The location of the various terminals shown and their connections are as follows: The terminals 202 and 203 are on the protector side of the main frame and are connected by means of a duplex jumper with the terminals 200 and 201 on the switch board side of the main frame. These latter terminals are connected by a 90 cable pair with the terminals 196 and 198, which are the line terminals of the terminal set comprising terminals 196, 197, and 198 located on the vertical side of the I. D. F. From the three terminals of this set, conductors 204, 205, and 206 extend to an individual line switch similar to the line switch C (Fig. 1). This is the calling branch of 95 the line and provides for outgoing service. Since the line shown is a two party line, two called line branches will be required to furnish incoming service, and it has been previously assumed that the branches to be used 100 are the ones comprising the two sets of normal conductors shown. Terminal sets 193-194-195 and 190-191-192 are accordingly connected by means of triplex jumpers to the terminal set 196-197-198. 105 There being only two jumpers to be multiplied, they may readily be connected direct to terminal set 196-197-198, and separate multiple or "idler" terminal blocks need not be used. While for convenience both of the 110 called line branches of the party line 212-213 have been shown as extending from the same group of connectors, it will be understood that by the provision of the intermediate distributing frame the party 115

120

125

130

line may just as well be connected up to be called from different groups of connectors. In other words, in connecting up a party line for service, it is only necessary to choose 5 an odd hundred call number and an even hundred call number, without regard to whether the two hundreds are in the same group of connectors or not.

While I have shown throughout the drawing 10 a plurality of batteries, it will be understood that in accordance with the usual practice there is preferably but one central battery having its positive pole grounded. Associated with the connector H, I have 15 shown a busy signaling machine Q, a ringing interrupter IR, and generators Gen¹ and Gen². The busy signaling machine and the ringing interrupter are of the type used in well known automatic telephone systems 20 and need not be described in detail. The generators Gen¹ and Gen² preferably deliver alternating current differing in frequency, and providing for selective ringing on the well known harmonic principle.

25 Having given a brief description of the apparatus involved, I will now proceed to an explanation of the operation thereof. For this purpose it will be assumed that the subscriber at substation A desires to obtain 30 a connection with the subscriber at substation A', this being the complete circuit connection shown in the drawings. The telephone number of substation A' is 3115. After describing the establishment and release 35 of the above connection, an explanation will be made of the operation of the connector H in calling the substation A², telephone number 3425, which substation is on the same line with substation A'.

40 To proceed, when the subscriber at substation A removes his receiver to initiate the call, an energizing circuit is completed for the line relay 16 of the individual line switch C as follows: ground at G', resting contact of 45 armature 19 and the said armature, conductor 12, substation A, conductor 13, armature 20 and its resting contact, and the winding of relay 16 to battery. Upon energizing, relay 16 closes the following circuit: ground 50 at G², armature 21 and its working contact, winding of switching relay 17, winding of cut-off relay 15, and the stepping magnet to battery. Simultaneously with the closure of the above circuit, the line relay 16 connects 55 the private or test wiper 41 with the junction point 30 as follows: test wiper 41, armature 24 and its resting contact, working contact of armature 22 and the said armature to junction point 30. It is understood 60 that the wipers of the line switch are normally in engagement with some contact set in the bank, and the operation now depends upon whether the contact set upon which the wipers are now resting is busy or not. 65 If this contact set is busy, the test contact

which is engaged by the test wiper 41 will have a ground potential upon it, resulting in the energization of the stepping magnet 18 and the short circuiting of the relays 15 and 17. The circuit for the stepping magnet 18 is as follows: ground on test contact engaged by wiper 41, wiper 41, armature 24 and its resting contact, working contact of armature 22 and said armature, junction point 30, winding of stepping magnet 18 to 70 battery. Thus it will be seen that the relays 15 and 17 will be short circuited by ground potential applied to the upper terminal of relay 15 by way of junction point 30 as long as the wiper 41 engages busy or grounded contacts. By the energization of the stepping magnet 18, the switch wipers are advanced to the next contact set, and since the stepping magnet interrupts its own circuit, the advance of the wipers will be continued 75 through the vibratory operation of the stepping magnet as long as the test wiper 41 continues to engage grounded or busy test contacts. When an idle or ungrounded test contact is reached, which we will assume to 80 be the test contact 44, the operation of the stepping magnet will cease; and the relays 15 and 17 being no longer short circuited, will energize over the previously traced circuit extending from ground G². Relays 15 85 and 17 are of sufficient resistance to prevent the energization of the stepping magnet 18. By the conjoint action of the cut-off relay 15 and the switching relay 17 the incoming line conductors 12 and 13 are disconnected 90 respectively from ground G² and the winding of the line relay 16 at the line switch C, and are extended by way of line wipers 42 and 40, bank contacts 45 and 43, and normally closed contacts of the switching relay 53 to 95 ground G³ and the winding of the line relay 50 of the selector E. The switching relay 17 also has the function of shifting the connection of the test wiper 41, whereby the test wiper is connected to the upper terminal of 100 the said relay 17.

When the conductors of the calling line are extended to the first selector E, the line relay 50 of the selector is energized over the calling subscriber's loop and completes the 115 usual energizing circuit for the slow acting release relay 51. Relay 51, upon energizing, completes a holding circuit for the relays 15 and 17 of the line switch C as follows: ground at G⁵, working contact of armature 120 62 and the said armature, conductor 46, bank contact 44, test wiper 41, armature 24 and its working contact, winding of relay 17, winding of relay 15, and the winding of the stepping magnet 18 to battery. The line 125 relay 16 of the line switch C is slow releasing so that it retains its armature attracted until after the above holding circuit has been established. A branch of the holding circuit extends from junction point 31 by 130

way of conductor 28 to multiple test contacts in the banks of the connector switches which have access to the line of substation A. Relay 17 is of lower resistance than relay 15 and these test contacts are brought sufficiently near to ground potential to render the line of substation A busy. Although I do not restrict myself to any particular values, relay resistances which give good results in practice are as follows: relay 15, 800 ohms; relay 16, 500 ohms; and relay 17, 200 ohms. The stepping magnet 18, of course, is of comparatively low resistance, preferably of about 40 or 50 ohms.

15 Returning to the selector E, when the conductor 46 was grounded by the energization of relay 51, circuits were closed simultaneously through the upper and lower windings of switching relay 53. The circuit 20 through the lower winding extends from grounded conductor 46 by way of junction point 68, the lefthand interrupter contact of the rotary magnet 56, armature 59 and its resting contact, and the lower winding of 25 relay 53 to battery. The circuit through the upper winding is a branch of the above circuit beginning at the junction point 69. Relay 53 is differentially wound and therefore is not energized at this time.

30 The foregoing operations have all occurred in response to the removal of the receiver at substation A. The calling subscriber may now operate his calling device in accordance with the first digit of the desired number, 35 thereby producing a series of three interruptions in the circuit of the line relay 50 of the selector E. In response to these interruptions of its circuit, the line relay 50 is deenergized a corresponding number of 40 times and at each deenergization transmits an impulse to the vertical magnet 54 as follows: ground at G⁴, armature 61 and its resting contact, resting contact of armature 58 and the said armature, armature 63 and 45 its working contact, winding of low resistance slow acting relay 52, and the winding of the vertical magnet 54 to battery. In response to these impulses, the vertical magnet is operated to raise the selector switch shaft step by step until wipers 80, 81, and 82 arrive opposite the third horizontal level of the bank contacts. The slow acting relay 52 is energized in series with the vertical magnet 54 and retains its armature attracted during the series of impulses in order to hold open a circuit for the rotary magnet 56 which is prepared by the closure of the off-normal springs 67 by the first upward movement of the shaft. At the end of 50 the vertical movement of the switch, the slow acting relay 52 is deenergized to complete the circuit of the rotary magnet 56 as follows: ground at G⁵, working contact of armature 62 and the said armature, conductor 46, junction point 68, lefthand inter- 55 rupter contact of the rotary magnet 56, armature 59 and its resting contact, armature 64 and its working contact, armature 65 and its resting contact, righthand interrupter contact of the rotary magnet 56 and 60 the winding of the said magnet, and the off-normal springs 67 to battery. The rotary magnet 56 is accordingly energized and the wipers 80, 81, and 82 are rotated into engagement with the first set of bank contacts in the level opposite which they are raised. Near the end of the stroke, the rotary magnet opens its interrupter contacts, thereby breaking its own circuit and also the 65 previously traced circuit through the lower winding of the switching relay 53. The operation now depends upon whether the contact set which is now engaged by the selector wipers is busy or idle. If this contact set is busy, the test contact engaged by 70 the test wiper 81 will have a ground potential upon it, whereupon current flow is maintained in the lower winding of relay 53 regardless of the operation of the rotary magnet, the circuit being as follows: grounded test contact, test wiper 81, armature 59 and its resting contact, and the lower winding of relay 53 to battery.

75 Since the relay 53 does not energize under these circumstances, when the rotary magnet 56 deenergizes, its energizing circuit is reestablished and the well known vibratory action is set up, whereby the switch wipers are advanced step by step as long as the test wiper 81 continues to engage grounded 80 or busy test contacts. When an idle or ungrounded test contact is reached, assumed to be the test contact 84, the instant the rotary magnet 56 opens its lefthand interrupter contact current will cease to flow in the lower winding of relay 53. There being now no opposition to the magnetizing effect of its upper winding, relay 53 energizes at once and at its armature 59 opens 85 the circuit of the rotary magnet, whereby the further advance of the switch is prevented. The relay 53 also opens a contact in the circuit of release magnet 55 at its armature 58 in order to provide against the release of 90 the switch upon the deenergization of relays 50 and 51 which occurs an instant later; and at its armatures 60 and 57 disconnects the line conductors 12 and 13 respectively, from ground G³ and from the line relay 50 and extends them by way of line wipers 82 and 80, bank contacts 85 and 83, and conductors 142 and 140 to the line relays 100 and 102 of the connector H (Fig. 2). The 95 following circuit is thereupon established: ground at G⁷, lower winding of relay 104, winding of relay 102, line conductor 142; bank contact 85, line wiper 82, working contact of armature 60 and the said armature, bank contact 45, line wiper 42, armature 25 and its working contact, line con- 100

105

110

115

120

125

130

ductor 12, substation A, line conductor 13, working contact of armature 23 and the said armature, line wiper 40, bank contact 43, armature 57 and its working contact, line wiper 80, bank contact 83, conductor 140, and the winding of the relay 100 to battery. Upon the closure of the above circuit, relays 100, 102, and 104 are energized in series. The energization of relay 100 is followed by the energization of the slow acting release relay 101, which closes a holding circuit for the selector E and line switch C as follows: ground at G⁸, working contact of armature 118 and the said armature, conductor 141, bank contact 84, test wiper 81, and the lefthand interrupter contact of the rotary magnet 56 to junction point 68, where it joins the previously described holding circuit extending back to the individual line switch C. The switching relay 53 is, of course, maintained energized over the branch circuit extending from junction point 69 to its upper winding.

Returning to the connector H, the energization of the line relay 102 is without particular function at this time. The release relay 101, in addition to grounding the conductor 141 as described, also connects ground G⁸ to the junction of relays 102 and 104, thereby short circuiting the lower winding of the latter relay. Relay 104 does not deenergize, however, owing to a locking circuit which has been established over the following path: ground at G⁸, working contact of armature 118 and the said armature, conductor 141, armature 123 and its resting contact, armature 127 and its working contact, and the upper winding of relay 104 to battery. When relay 104 is in energized position, the short circuiting path around the off-normal springs 124 and 125 is opened at armature 126, and the ringing current generator Gen' is connected for service at armature 128.

The calling subscriber may now proceed to dial the second digit in the number of the substation A', which is the digit 1. It follows accordingly, that a single interruption is produced in the energizing circuit of the line relays 100 and 102, resulting in a single momentary deenergization of both relays. The deenergization of relay 102 is of no effect; relay 100, however, transmits an impulse to the slow acting relay 103 over the following path: ground at G⁸, armature 117 and its resting contact, armature 119 and its working contact, winding of relay 103, resting contact of armature 131 and the said armature, and the low resistance primary winding of the busy signaling machine Q to battery. Relay 103 is energized for an instant in response to a momentary flow of current in the above circuit and at its armature 123 closes a circuit for the private magnet 111 as follows: grounded

conductor 141, armature 123 and its working contact, and the winding of the private magnet 111 to battery. Upon the deenergization of the relay 103 and the private magnet 111, the latter advances the side switch wipers 115 and 116 from first to second position in the usual manner. It is to be noted that when the relay 103 is energized in response to the calling of the digit 1, the locking circuit of relay 104 is broken momentarily at the resting contact of armature 123. Relay 104 is a slow acting relay and is so adjusted that it will not deenergize when its locking circuit is opened only momentarily as occurs under the present circumstances.

The calling subscriber may now operate his calling device in accordance with the next digit of the desired number, thereby producing as before an interruption in the energizing circuit of the line relays 100 and 102. The consequent deenergization of relay 102 is again of no effect; but relay 100, upon deenergizing, transmits as previously an impulse to the slow acting relay 103, and also, since side switch wiper 115 is now in its second position, an impulse to the vertical magnet 109. The vertical magnet 109 and the slow acting relay 103 are therefore energized in parallel. By the operation of the vertical magnet, the connector shaft is raised one step whereby the wipers 180, 181, and 182 are brought into position opposite the first horizontal level of bank contacts. By the operation of relay 103, the private magnet 111 is actuated as before to advance the side switch wipers 115 and 116 from second to third position. It should be mentioned at this point that at the first upward movement of the switch shaft the off-normal springs 113 and 114 are closed in order to guard against a prolonged opening of the locking circuit of relay 104, which would have taken place had the digit just called been some digit other than the digit 1, for the relay 103 being slow acting remains energized continuously during a series of impulses. Thus it will be seen that relay 103 controls the locking circuit of relay 104 only during the first series of impulses which is directed to the connector H and that during subsequent series of impulses the said relay 104 will remain locked up independent of relay 103 by way of off-normal springs 113 and 114.

The calling subscriber may now call the final digit in the number of substation A', thereby producing a series of five interruptions in the circuit of the line relays 100 and 102. The resulting deenergizations of the line relay 100, serve to cause momentary current impulses to flow in the winding of relay 103, which relay being slow acting remains energized continuously during the series of impulses and maintains an energizing circuit for the private magnet 111. Side

switch wiper 115 having moved from second to third position, the vertical magnet 109 is not now actuated; but instead the rotary magnet 110 is operated under the control of the line relay 102 in a manner now to be described. At the first deenergization of relay 102, a circuit is closed to the rotary magnet 110 as follows: ground at G^s , working contact of armature 118 and the said 10 armature, conductor 141, armature 120 and its resting contact, armature 129 and its resting contact, winding of rotary magnet 110 and the side switch wiper 115 in third position to battery. The rotary magnet 110 is accordingly operated to advance the 15 wipers 180, 181, and 182 into engagement with the first set of contacts in the first level. At the next deenergization of relay 102, the same circuit is again closed for the 20 rotary magnet, whereupon the switch wipers are advanced into engagement with the second set of contacts in the first level. Upon the second rotary step, the rotary off-normal springs 124 and 125 are permitted to close 25 and it follows therefore that when the relay 102 is energized immediately following its second deenergization, a circuit will be completed for the rotary magnet 110 over the following path: grounded conductor 141, 30 armature 120 and its working contact, armature 122 and its working contact, off-normal springs 125 and 124, armature 129 and its resting contact, winding of the rotary magnet 110 and the side switch wiper 115 in 35 third position to battery. The rotary magnet is accordingly energized to advance the switch wipers to the third set of contacts in the first level. The deenergization and energization of relay 102 in response to the third 40 interruption of its circuit likewise produces two closures of the circuit of the rotary magnet 110, the circuit being closed once at the resting contact of armature 120 and again at the working contact of the same armature. It will be seen then that the rotary magnet will be operated once upon the first 45 interruption of the circuit of the relay 102 and twice at each succeeding interruption. Since in the present case five interruptions 50 are produced, the switch wipers will be advanced nine steps into engagement with the ninth set of contacts in the first level which, by referring to Fig. 3, will be seen to be the ones associated with the substation A'.

55 At the end of the final series of impulses, the slow acting relay 103 deenergizes and its upper armature 122 breaks the circuit of the rotary magnet. At its lower armature 123, relay 103 breaks the circuit of the private 60 magnet 111, whereupon the said magnet is deenergized to advance the side switch wipers 115 and 116 to fourth position, it being assumed that the line of substation A' was idle when called. By the advance of the side 65 switch wiper 116 to its fourth position, an energizing circuit is completed for the cut-off relay 15' of the line switch associated with the called line as follows: ground at G^{10} , side switch wiper 116 in fourth position, private or test wiper 181, bank contact 184, conductor 206, winding of cut-off relay 15' and the winding of the stepping magnet 18' to battery. The cut-off relay 15', owing to its high resistance, is energized without operating the stepping magnet 18' and disconnects the line conductors 204 and 205 from their normal battery and ground connections in the line switch. The advance of the side switch wipers 115 and 116 to fourth position also closes an energizing circuit 70 for the wiper switching relay 108 in an obvious manner and by the operation of this relay, a signaling circuit is completed which may be traced as follows: ground at G^{11} , generator Gen', ringing interrupter IR, 75 working contact of armature 128 and the said armature, resting contact of armature 134 and the said armature, armature 136 and its working contact, line wiper 182, bank contact 185, terminals 192, 198, 201, and 203, line conductor 213, the ringer 5' and condenser 6' at substation A', line conductor 212, terminals 202, 200, 196, and 190, bank contact 183, line wiper 180, working contact of armature 135 and the said armature, armature 132 and its resting contact, lower winding of the ring cut-off relay 107, and the central office battery to ground G^{12} . By the operation of the ringing interrupter IR, the generator Gen' is intermittently disconnected and a booster battery substituted therefor, thereby producing an intermittent ringing of the bell at substation A'. The relay 107 is so adjusted that it will not energize so long as the receiver at the called 80 substation remains on the hook.

When the called subscriber at substation A' takes down his receiver in response to the ringing of his bell, the ring cut-off relay 107 in the signaling circuit is instantly 85 energized, irrespective of the position of the ringing interrupter IR, and completes a locking circuit for itself as follows: ground at G^{12} , the lower pair of off-normal springs, the working contact of armature 133 and the said armature, and the upper winding of the relay 107 to battery. As a further result of its energization, relay 107 disconnects its lower winding and the lead 90 from the ringing current generator at its armatures 132 and 134 respectively, and at the working contacts of these same armatures finally completes the talking connection to the called line. Current for the transmitter at substation A' is supplied through 95 the windings of the double wound impedance coil 106 which is connected in bridge of the called line in series with the battery in an obvious manner. Current for the transmitter at the calling substation A is 100

105 110 115 120 125 130

supplied through the windings of the line relays 100 and 102. The path of the voice currents has been drawn in heavy lines and will require no detailed explanation.

- 5 At the end of the conversation both subscribers will replace their receivers. By the replacement of the receiver at substation A, the energizing circuit of the line relays 100 and 102 of the connector H is broken.
- 10 The resulting deenergization of the line relay 100 is followed after a brief interval by the deenergization of the slow acting relay 101, resulting in the closure of the circuit of the release magnet 112. The connector H is accordingly restored to normal position through the medium of the release magnet 112 as usual, the circuit of the release magnet being opened when the switch shaft reaches its lowest position. As a further result of 20 the deenergization of relay 101, ground G^s is disconnected from conductor 141, thereby opening the holding circuit over which the relay 53 of selector E and the relays 17 and 15 of the line switch C have been maintained energized. Upon the deenergization of relay 53, the circuit of the release magnet 55 of the selector is completed and the selector E is therefore restored to normal position in the same manner as was the connector H.
- 30 The deenergization of relays 17 and 15 of the line switch C disconnects the line of substation A from the line wipers of its individual switch and places the switch in condition for another call. All the apparatus involved in the connection has now been restored to normal position.

I will now explain briefly the operation of the connector H when the substation A² is called, in order that its operation in calling an even hundred station may be understood. Assuming that the telephone number at substation A² is 3425, the first series of impulses directed toward the connector H will consist of four interruptions of the line circuit including the line relays 100 and 102, corresponding with the digit 4 of the called number. The line relays will accordingly deenergize momentarily four times, resulting in the transmission by the line relay 100 of a series of four impulses to the slow acting relay 103. The slow acting relay 103 during the continuance of the series of impulses maintains its armature continuously attracted, and as before described, closes an energizing circuit for the private magnet 111 and opens the locking circuit of the slow acting relay 104. At the end of the series of impulses, relay 103 and private magnet 111 deenergize and the side switch is advanced by the latter to second position. In the case where the substation A² was the called substation, the first series of impulses directed to the connector H consisting of a single interruption of the line circuit, it was explained that the resulting energization of

relay 103 was not of sufficient duration to bring about the deenergization of the slow acting relay 104. In the present case, however, since the digit called is 4 instead of 1, the relay 103 will remain energized four times as long as in the former case, thus insuring that relay 104 will deenergize. Upon retracting its armatures, relay 104 breaks its own locking circuit at armature 127 so that it cannot again energize during the same call; short circuits the off-normal springs 124 and 125 at its armature 126; and at its armature 128 connects the ringing current generator Gen². The vertical operation of the connector in response to the next digit of the number is the same as before. When the final digit is called, since the rotary off-normal springs 124 and 125 have been short circuited, the rotary magnet 110 will receive two impulses for each interruption of the line circuit, including the first interruption as well as the remaining ones. It follows that the switch wipers 180, 181, and 182 will be advanced ten steps into engagement with the contact set comprising bank contacts 186, 187, and 188, which is the contact set associated with the substation A². During the signaling operation, the generator Gen² is in service, resulting in the actuation of the ringer 5² at the substation A², the ringer 5¹ at substation A' not being operated. When the subscriber at substation A² responds, the ringing current is cut off and the talking connection is completed as before described.

If in calling either substation A' or A², the called line had been busy, there would have been a ground potential on test contact 184. Under these circumstances when the slow acting relay 103 deenergizes at the end of the final series of impulses, its deenergization is not followed by the deenergization of the private magnet 111; but the latter is maintained energized over the test circuit extending as follows: grounded test contact 184, private or test wiper 181, side switch wiper 116 in third position, contact springs controlled by the armature 130 of test relay 105, winding of the test relay, contact springs controlled by the armature 123 of relay 103, and the winding of the private magnet 111 to battery. Upon energizing, the test relay 105 completes a locking circuit for itself and the private magnet 111; opens the circuit of the rotary magnet 110 at its armature 129; and at its armature 131 opens the circuit of relay 103 and connects the primary winding of the induction coil of the busy signaling machine Q to the lower heavy line conductor. The calling subscriber is thereby given a characteristic signal notifying him that the called line is busy and therefore inaccessible for the present.

It will be seen from the foregoing that I

have devised an automatic telephone system containing a number of features conducing to its increased usefulness and efficiency. While I have shown and described a specific embodiment of the various features, modifications may be made without departing from the scope of the invention. For example, a group of connectors such as the connector H, is not necessarily restricted to party line service, but any set of bank contacts in either the odd or even hundred may be cross connected at the intermediate distributing frame to an individual line, it being only necessary to install a substation on the line which has a ringer tuned to the proper frequency. Or if desired untuned ringers may be used on the individual lines which will respond to either frequency of ringing current, thus making it unnecessary to consider this detail at all. Moreover, if the exchange consists entirely of individual lines, the party line and selective ringing features may be cut out altogether. In an installation of this character, the intermediate distributing frame will be discarded, the normal conductors from the connector banks being terminated directly on the switch board side of the main distributing frame, and the frequency selecting armatures of the connectors such as the armature 128 of the connector H being omitted. It will be obvious also that the selective ringing feature of the invention will be of utility when used with the ordinary connectors of one hundred line capacity. Connectors thus equipped may be similar to the connector H except that they will have the ordinary one hundred point bank and that the circuits provided for the doubling up of the impulses to the rotary magnet will be omitted.

In view of these considerations, I do not wish to have the invention restricted to the precise form shown and described, but desire to include and have protected by Letters Patent all forms and modifications thereof which come within the scope of the appended claims.

What I claim as my invention is:

1. In a telephone system, a subscriber's line having an individual trunk selecting switch at the exchange, line, cut-off, and line switching relays in said switch, a stepping magnet, and a circuit completed by said line relay in response to the removal of the receiver at the substation on said line, said circuit including the other two relays and said magnet in series.

2. In a telephone system, a subscriber's line having an individual trunk selecting switch at the exchange, line, cut-off, and line switching relays in said switch, a stepping magnet, a circuit completed by said line relay in response to the removal of the receiver at the substation on said line, said circuit including the other two relays and

said magnet in series, a test wiper in said switch, and a branch of said circuit also completed by said line relay and extending from a point between the said magnet and cut-off relay to the said test wiper. 70

3. In a telephone system, a line extending to an exchange and provided with calling and called branches thereat, an individual trunk selecting switch for extending the calling branch and trunk lines accessible thereto, cut-off and line switching relays in said switch, third conductors associated with the called branch of said line and with the several trunk lines, an energizing circuit for both said relays completed via the third 80 conductor of a selected trunk line when the line is calling, and an energizing circuit for the said cut-off relay alone completing via the third conductor of the called branch when the line is called. 85

4. In a telephone system, a line provided with an individual trunk selecting switch at the exchange, a line relay controlling the operation of said switch, a switching relay for closing contacts in the line circuit after 90 said switch has operated, a cut-off relay for disconnecting said line relay, and an energizing circuit including said cut-off and switching relays in series. 95

5. In a telephone system, a line provided with an individual trunk selecting switch at the exchange, a line relay controlling the operation of said switch, a switching relay for closing contacts in the line circuit after 100 said switch has operated, a cut-off relay for disconnecting said line relay, a motor magnet for said switch, and an energizing circuit for the said cut-off and switching relays including said motor magnet. 105

6. In a telephone system, a line provided with an individual trunk selecting switch at the exchange, a line relay controlling the operation of said switch, a switching relay for closing contacts in the line circuit after 110 said switch has operated, a cut-off relay for disconnecting said line relay, a motor magnet for said switch, an energizing circuit for the said cut-off and switching relays including said motor magnet, closed by said line relay upon the initial operation of said 115 switch, and means including a test wiper of said switch for maintaining said cut-off and switching relays short circuited during the trunk selecting operation. 120

7. In a telephone system, a line provided with an individual trunk selecting switch at the exchange, a line relay controlling the operation of said switch, a switching relay for closing contacts in the line circuit after 125 said switch has operated, a cut-off relay for disconnecting said line relay, an energizing circuit for the cut-off and switching relays in series closed when the line is calling, and an energizing circuit for the cut-off relay alone closed when the line is called. 130

8. In a telephone system, trunk lines, an automatic trunk selecting switch controllable over a calling line to select an idle trunk, a differentially wound switching relay for 65
 5 closing the talking conductors through said switch after the same has operated, circuits for the two windings of said relay maintained closed during the trunk selecting operation to prevent said relay from energizing, said circuits being closed successively, and a third circuit for the relay winding included in said circuit which is closed last for preventing said relay from energizing before the trunk selecting operation has 70
 10 started.
9. In a telephone system, trunk lines, an automatic trunk selecting switch controllable over a calling line to select an idle trunk, a differentially wound switching relay for 75
 20 closing the talking conductors through said switch after the same has operated, circuits for the two windings of said relay maintained closed during the trunk selecting operation to prevent said relay from energizing on a busy trunk line, a stepping magnet for said switch, and contacts on said magnet for opening the circuit of one winding to permit said relay to energize when an idle trunk line is reached.
10. In a telephone system, trunk lines, an automatic switch controllable over a calling line to select an idle trunk, a differentially wound switching relay for closing the line conductors through said switch after the 80
 30 same has operated, circuits for the two windings of said relay closed before the trunk selecting operation is initiated, and means operated during the selecting operation to open the circuit of one winding of said relay 85
 40 as each successive trunk line is reached to permit its energization on any idle trunk line.
11. In a telephone system, trunk lines, an automatic switch controllable over a calling 90
 45 line to select an idle trunk, a differentially wound switching relay for closing the line conductors through said switch after the same has operated, circuits for the two windings of said relay closed before the 95
 50 trunk selecting operation is initiated, means operated during the selecting operation to open the circuit of one winding of said relay as each successive trunk line is reached to permit its energization on any idle trunk line, and test circuit connections for shunting 100
 55 said circuit opening means while the selector is passing busy trunk lines.
12. In a telephone system, a plurality of party lines, a plurality of groups of connectors, sets of fixed terminals for each station on each line, the terminal sets associated with stations on the same line being in different groups of connectors, and a plurality of sources of ringing current of differ- 105
 60 ent character associated with each group 110
 of connectors, together with means in each connector for selecting the proper source of ringing current and applying the same to the fixed terminals of a called station.
13. In a telephone system, a plurality of party lines, signals at the stations on each line responsive to different frequencies of ringing current, a plurality of groups of connectors, sets of fixed terminals for each station on each line, the terminal sets associated with stations on the same line being in different groups of connectors, a plurality of sources of ringing current of different frequency associated with each group of connectors, together with means in each connector for selecting the proper frequency of ringing current and applying the same to the fixed terminals of a called station to actuate the signal thereat.
14. In a telephone system, a plurality of party lines, signals at the stations on each line responsive to different frequencies of ringing current, a plurality of groups of connectors, sets of fixed terminals for each station on each line, the terminal sets associated with stations on the same line being in different groups of connectors, a plurality of sources of ringing current of different frequency associated with each group of connectors, together with means in each connector for selecting and operating mechanism in each connector, and means under control of the subscriber on a calling line for extending connection to an idle connector in one of said groups, and for controlling the mechanism thereof to 110
 15 connect with and selectively signal a wanted station.
15. In a telephone system, a connector switch having a movable terminal, a party line accessible to said terminal via as many 115
 45 paths as there are stations on the line, means for operating said connector to advance it to connect with said line, and means for predetermined over which path the connection is to be established.
16. In a telephone system, a connector switch having a movable terminal, a party line accessible to said terminal via as many paths as there are stations on the line, a corresponding plurality of generators of different electrical character, means in said connector for selecting one of said generators for connection to said line via said movable terminal, and means for predetermined 120
 50 the path over which the selected generator is to be connected.
17. In a telephone system, a connector switch having a movable terminal, a party line accessible to said terminal via as many paths as there are stations on the line, means for operating said connector in accordance with a digit in the call number of said line 125
 55 to connect its terminal thereto, and means

for predetermining in accordance with a previous digit the path over which the connection is to be established.

18. In a telephone system, an automatic connector switch having a pair of line wipers, a party line accessible to said wipers via as many paths as there are stations on the line, a corresponding plurality of generators of different electrical character, means for connecting any generator with said line via said wipers, and means in said connector for selecting a generator and for predetermining the path over which it is to be connected in accordance with a digit in the number of said line.

19. In a telephone system, an automatic connector switch, a party line, a plurality of stations on said line each provided with a set of fixed terminals in said connector, means for operating said connector to connect with said line via any set of fixed terminals, and selective ringing mechanism in said connector responsive to a digit in the call number of the wanted station on said line separate from the digit or digits which control the operation of said connector.

20. In a telephone system, an automatic connector switch provided with a set of movable terminals, a party line provided with a set of fixed terminals in said connector for each station on the line, sources of ringing current of different character associated with said connector, means for transmitting series of controlling impulses to said connector in accordance with the digits in the call number of a wanted station on said line, and mechanism in said connector responsive to one series of impulses for selecting one of said current sources while the movable terminals of said connector remain stationary in normal position.

21. In a telephone system, an automatic connector switch provided with a set of movable terminals, a party line provided with a set of fixed terminals in said connector for each station on the line, sources of ringing current of different character associated with said connector, means for transmitting series of controlling impulses to said connector in accordance with the digits in the call number of a wanted station on said line, mechanism in said connector responsive to one series of impulses for selecting one of said current sources while the movable terminals of said connector remain stationary in normal position, and operating mechanism in said connector responsive to another series of impulses for advancing said movable terminals into engagement with one of said sets of fixed terminals.

22. In a telephone system, an automatic connector switch provided with a set of movable terminals, a party line provided

with a set of fixed terminals in said connector for each station on the line, sources of ringing current of different character associated with said connector, means for transmitting series of controlling impulses to said connector in accordance with the digits in the call number of a wanted station on said line, and mechanisms in said connector independently controlled responsive to separate series of impulses for selecting, respectively, the proper current source and a set of said fixed terminals, in order to signal a desired station on said line.

23. In a telephone system, an automatic connector switch, a party line, a plurality of stations on said line each provided with a set of fixed terminals in said connector, operating and selective ringing mechanisms in said connector, and means for transmitting a plurality of series of controlling impulses to said connector in accordance with digits in the call number of a station on said line, said selective ringing mechanism being responsive to one series of impulses and the said operating mechanism 90 being responsive to the remaining series of impulses.

24. In a telephone system, an automatic connector switch, a party line, a plurality of stations on said line each provided with a set of fixed terminals in said connector, operating and selective ringing mechanisms in said connector, means for transmitting a plurality of series of controlling impulses to said connector in accordance with digits 100 in the call number of a station on said line, and a relay responsive to the first series of impulses for controlling said ringing mechanism, and responsive to succeeding series of impulses for controlling the said operating mechanism.

25. In a telephone system, an automatic connector switch, a party line, a plurality of stations on said line each provided with a set of fixed terminals in said connector, operating and selective ringing mechanisms in said connector, and means for transmitting a plurality of series of controlling impulses to said connector in accordance with digits 110 in the call number of a station on said line, the said ringing mechanism and the said operating mechanism being separately responsive to separate series of impulses.

26. In a telephone system, a party line connector switch, a pair of ringing generators of different electrical character for selective signaling purposes, a line relay in said connector, and a second relay energized in series with said line relay and under control of said line relay for selecting either 125 one of said generators.

27. In a telephone system, a party line connector switch operated in response to a

- plurality of digits of a called number, a pair of ringing generators of different electrical character for selective signaling purposes, and a relay in said connector controlled 65
5 in accordance with the first of said digits and having contacts for connecting up either generator for use.
28. In a telephone system, a party line connector switch, a pair of ringing generators of different electrical character for selective signaling purposes, a slow acting relay in said connector, and ringing circuits controlled by said relay for determining which of said generators is to be used. 70
- 15 29. In a telephone system, a party line connector switch, a pair of ringing generators of different electrical character for selective signaling purposes, a slow acting relay in said connector automatically energized to select one of said generators, and means for deenergizing said relay to select the other generator. 75
- 20 30. In a telephone system, a party line connector switch, a pair of ringing generators of different electrical character for selective signaling purposes, a slow acting relay automatically energized to select one of said generators, and means responsive when a series of controlling impulses is 80
25 transmitted to said connector to deenergize said relay to select the other generator. 85
- 30 31. In a telephone system, a line terminating in an automatic switch, a stepping relay and an operating magnet in said switch, a circuit for said relay including 90
35 said line, a calling device operable in accordance with digits in a called telephone number for producing interruptions in said circuit to cause momentary deenergizations 95
40 of said relay, the number of interruptions produced being always equal to the digit called, and circuits controlled by said relay for transmitting a current impulse to said magnet at each deenergization and at 100
45 each subsequent energization. 105
32. In a telephone system, an automatic switch, a stepping relay and an operating magnet in said switch, means for energizing and deenergizing said relay a plurality of 110
50 times, circuits controlled by said relay for transmitting a current impulse to said magnet at each deenergization and at each energization, and mechanism for causing the impulse due to the energization following 115
55 the first deenergization to be omitted. 120
33. In a telephone system, an automatic switch, a stepping relay and an operating magnet in said switch, means for momentarily deenergizing said relay a plurality of 125
60 times in accordance with a digit in a called telephone number, circuits controlled by said relay for transmitting a current impulse to said magnet at each deenergization and at each subsequent energization,
- there being mechanism for causing the impulse to be omitted on the initial energization of said relay, and mechanism controlled in accordance with another digit in the number for causing another impulse to be omitted. 70
34. In a telephone system, an automatic switch for connecting calling and called lines, means for transmitting a plurality of series of impulses to said switch to operate the same, primary operating mechanism responsive to one series of impulses for advancing said switch in a number of steps equal to the number of impulses received, and secondary operating mechanism responsive to another series of impulses 80 for further advancing said switch in a number of steps greater than the number of impulses received. 85
35. In a telephone system, an automatic step by step switch for connecting calling and called lines, means for transmitting a plurality of series of current impulses to said switch, operating mechanism responsive to a series of impulses for advancing said switch a number of steps which is a multiple of the number of impulses in the series, and mechanism controlled in accordance with a previous series of impulses for causing one step to be omitted in case the said previous series contained a particular 95 number of impulses. 90
36. In a telephone system, an automatic step by step switch for connecting calling and called lines, a line relay in said switch responsive to a series of controlling impulses directed to said switch, a wiper shaft, a magnet controlled by said relay to advance said shaft in a variable number of steps greater than the number of impulses in said series, a second relay controlled according to a previous series of impulses, and cooperating means controlled by said shaft and the said second relay for determining the exact number of steps said shaft is advanced. 100
37. In a telephone system, means including an automatic step by step switch for connecting a calling and called line, means for transmitting series of impulses over the calling line to control said switch, an operating magnet responsive to a series of impulses to advance said switch a variable number of steps, and means for determining the number of steps the switch will be so advanced. 110
38. In a telephone system, means including an automatic step by step switch for connecting a calling and called line, means for transmitting series of impulses over the calling line to control said switch, an operating magnet and means for actuating it a variable number of times in response to any particular series of impulses, and sepa- 115
120
125

rate means for determining the number of times said magnet is to be actuated.

39. In a telephone system, means including an automatic step by step switch for connecting a calling and called line, means for transmitting successive series of impulses over the calling line to control said switch, an operating magnet responsive to a particular series of impulses to advance said switch a certain number of steps, and a second operating magnet responsive to a like series of impulses to advance said switch a different number of steps.

40. In a telephone system, an automatic switch, primary and secondary operating magnets in said switch, means for transmitting series of controlling impulses to said switch, a line relay responsive to a series of impulses for operating the primary magnet a number of times, and a second relay responsive to a like series of impulses for operating the secondary magnet a different number of times.

41. In a telephone system, an automatic switch, primary and secondary operating magnets in said switch, means for transmitting series of controlling impulses to said switch, a line relay responsive to a series of impulses for operating the primary magnet a number of times, and a second relay responsive to a like series of impulses for operating the secondary magnet a greater number of times.

42. In a telephone system, an automatic switch, two groups of line terminals in said switch, the terminals of one group alternating in position with the terminals of the other group, a pair of ringing generators, a movable terminal in said switch, means for operating the movable terminal to connect with a line terminal of either group, and means dependent upon the selection of a certain group of lines for selecting a particular one of said generators.

43. In a telephone system, an automatic switch, two groups of line terminals in said switch so positioned that every two adjacent terminals belong to different groups, a pair of ringing generators, a movable terminal in said switch, means controlled over a calling subscriber's line for advancing said movable terminal into engagement with a desired line terminal in either group, and means dependent upon the selection of a certain group of lines for selecting a particular one of said generators.

44. In a telephone system, an automatic switch having a movable terminal, two series of like numbered line terminals in said switch, means for transmitting two series of controlling impulses to said switch, and operating mechanism responsive to said impulses for advancing said movable terminal past line terminals in both series and

into engagement with one of the two line terminals which correspond to the series of impulses received.

45. In a telephone system, an automatic switch having a movable terminal, two series of like numbered line terminals in said switch, means for transmitting two series of controlling impulses to said switch, operating mechanism responsive to said impulses for advancing said movable terminal past line terminals in both series and into engagement with one of the two line terminals which correspond to the series of impulses received, and means for determining in accordance with a prior series of impulses which line terminal is to be connected with.

46. In a telephone system, an automatic switch, a series of called line terminals in said switch numbered in accordance with the two final digits in telephone call numbers, a second series of called line terminals in said switch having like numbers with said first series, means for operating said switch in accordance with the two final digits in a telephone call number to connect with a called line terminal in either series, and relay mechanism operated in accordance with a prior digit in the telephone call number for selecting the series.

47. In a telephone system, an automatic switch having a movable terminal, two groups of fixed terminals in said switch, means for operating said switch to connect its movable terminal with a fixed terminal in either group, an electromagnet in said switch and means for energizing and de-energizing it, and circuits controlled thereby whereby if said switch is operated when the magnet is energized a terminal in one group will be connected with and whereby if the switch is operated when the magnet is deenergized a terminal in another group will be connected with.

48. In a telephone system, an automatic switch, line terminals in said switch divided into groups, means for transmitting series of controlling impulses to said switch, and a slow acting relay in said switch responsive to a series of impulses to select a group of said terminals.

49. In a telephone system, an automatic switch, line terminals in said switch divided into groups, means for transmitting series of controlling impulses to said switch, a slow acting relay for selecting groups of terminals, means for automatically energizing said relay, and means for deenergizing said relay in response to a particular series of impulses.

50. In a telephone system, an automatic switch, line terminals in said switch divided into groups, means for transmitting series of controlling impulses to said switch, a re-

- 5 lay in said switch energized automatically to select one group of said terminals, and means for deenergizing said relay to select another group of terminals in response to a particular series of impulses. 65
- 5 51. In a telephone system, an automatic switch, line terminals in said switch divided into groups, means for transmitting series of controlling impulses to said switch, and 70
- 10 a relay in said switch responsive to one series of impulses and irresponsible to another series of impulses for determining the selection of a desired group of said terminals. 75
- 15 52. In a telephone system, an automatic switch, line terminals divided into groups and subgroups accessible to said connector, means for transmitting three series of current impulses to said connector, relays responsive to one series having sole control 80
- 20 of the group selection, and operating magnets responsive to the two remaining series for selecting a subgroup in the selected group and an individual terminal in the 85
- 25 selected subgroup. 90
53. In a telephone system, a party line connector switch, a pair of ringing generators of different electrical characters for selective signaling purposes, a line relay in 95
- 30 said connector, a second relay under control of said line relay, and means dependent on the energized or deenergized position of said second relay for selecting either one of said generators. 100
- 35 54. In a telephone system, an automatic switch, line terminals in said switch divided into groups, means for transmitting series of controlling impulses to said switch, a line relay in said switch, a selecting device 105
- 40 consisting solely of relays controlled by said line relay responsive to the first series of impulses for selecting a desired one of said groups, a progressively movable switching mechanism controlled by said line relay 110
- 45 responsive to another series of impulses for selecting a desired line in the selected group, and a circuit changing device for shifting the control of said line relay from the relay selecting device to the switching mechanism. 115
- 50 55. In a telephone system, an automatic switch, line terminals in said switch divided into groups and subgroups, means for transmitting series of impulses to said switch, a line relay in said switch, a selecting device 120
- 55 consisting solely of relays controlled by said line relay responsive to the first series of impulses for selecting a desired one of said groups, a progressively movable switching mechanism controlled by said line relay 125
- 60 responsive to the next series of impulses for selecting a desired subgroup in the selected group, another progressively movable switching mechanism controlled by
- 65 said line relay responsive to the next series of impulses for selecting a desired line in the selected subgroup, and circuit changing means for shifting the control of said line relay from the relay selecting device to the first switching mechanism and from the first switching mechanism to the second. 70
- 70 56. In an automatic telephone system, a plurality of party lines each terminating in an automatic switch, said switches being operable to extend outgoing calls from said lines, means for distributing incoming calls to the stations on said lines comprising groups of connector switches, different classes of called line branches corresponding to the different stations on a line, there being a plurality of branches of each class accessible to the connectors of each of said groups, a distributing frame wherat each party line may be connected at will with any desired branch in each of said classes, certain party lines being each connected to branches accessible to the same group of connectors and certain other party lines being each connected to branches accessible to different groups of connectors, and selective signalling mechanism in each connector in each group, whereby in the case of any line which happens to be connected with a plurality of branches which are accessible to the same group of connectors the stations corresponding to such branches may be selectively signalled from any connector in the group. 80
- 85 57. In a telephone system, a plurality of party lines incoming to an exchange, calling branches for said lines terminating in automatic switches for use in extending outgoing calls, a plurality of groups of connector switches, a plurality of called line branches terminating in each group of connectors, a permanent connection between each line and its associated calling branch, a distributing frame on which said party lines are temporarily connected to said called line branches by means of jumpers, some lines being connected each to a plurality of branches terminating in the same group of connectors and other lines being connected each to a plurality of branches terminating in different groups of connectors, and selective signalling means in each connector of each group for signaling the station corresponding to any called branch to which such connector has access. 95
- 95 58. In a telephone system, a line terminating in an automatic switch, trunk lines, means for controlling said switch over said line to automatically select an idle trunk line, a differentially wound switching relay for extending the said line to the selected trunk line after the switch has operated, an energizing circuit for said switching relay including one winding thereof, a second

- circuit including the other winding of said relay for preventing the relay from energizing, means for opening the said second circuit at the beginning of the trunk selecting 5 operation, a test wiper for said switch, and a third circuit including said test wiper for shunting the break in the said second circuit to prevent said relay from energizing until the trunk selecting operation is completed.
59. In a telephone system, trunk lines arranged in groups, a line terminating in an automatic switch, means for directively controlling said switch over said line to select 15 one of said trunk groups, means for operating said switch automatically to then select an idle trunk in the selected group, a differentially wound switching relay for extending the said line to the selected trunk after the 20 switch has operated, and circuits for both windings of said relay maintained closed during the automatic trunk selecting move-

ment to prevent the energization of said relay.

60. In a telephone system, trunk lines arranged in groups, a line terminating in an automatic switch, means for directively controlling said switch over said line to select one of said trunk groups, means for operating said switch automatically to then select an idle trunk in the selected group, a differentially wound switching relay for extending the said line to the selected trunk after the switch has operated, an energizing circuit for said switching relay including 30 one winding thereof, a test wiper for said switch, and another circuit for said relay including the other winding thereof and said test wiper for preventing the energization of said relay during the automatic trunk selecting 35 operation.

Signed by me at Chicago, Cook County, Illinois, this 22nd day of June, 1917.

RODNEY G. RICHARDSON.
